L. O. Hutchinson

UNITED STATES PATENT OFFICE

ROSALYE SCHWERIN, OF RUTHERFORD, NEW JERSEY

TOOTHBRUSH

Application filed March 6, 1931. Serial No. 520,580.

This invention relates to tooth brushes and has for an object a tooth brush in which the bristles are caused to vibrate transversely of the brush to thereby move over the teeth toward and away from the gums.

A tooth brush embodying the invention comprises a handle which slidably supports a brush provided with longitudinal rows of bristles. Between adjacent rows of bristles are provided undulating members which cause transverse vibration of the bristles upon relative movement of the brush and handle. In use, the brush is held stationary with its bristles engaging the teeth and the handle is reciprocated relative to the brush to cause the bristles to move toward and away from the gums. The brush may be held stationary either by pressure against the teeth or by the lips.

Other objects, novel features and advantages of this invention will be apparent from the following specification and accompanying drawings, wherein

Fig. 1 is a rear view of one embodiment of the invention;

Fig. 2 is a side view;

Fig. 3 is a front view, and

Fig. 4 is an enlarged section on the line 4—4 of Fig. 1.

A handle 10 has two rods or the like 11 projecting from one end and on the rods is mounted a slide 12 having passages through which the rods extend. The slide 12 is provided with a plurality of longitudinal rows of bristles 13. A head 14 is mounted on the ends of the rods 11 by means of screws 15 having threaded engagement with the rods 11. A plurality of undulating bars 16 extend from the handle 10 to the head 14 between adjacent rows of spindles. Relative movement of the slide and handle is productive of transverse movement of the bristles due to the engagement of the undulations of the bars 16 with the bristles.

The brush above described is utilized in the usual way to brush the teeth. Relative movement of the slide and handle will occur whenever the slide is held stationary, either due to friction of the bristles against the teeth or by engagement with the lips. Also,

at the end of each usual brushing stroke, the handle may be moved beyond the movement of the slide. The bristles are thus caused to vibrate toward and away from the gums in the manner suited to cleanse the crevices between the teeth.

A worn brush may easily be renewed by merely detaching the head 14 and sliding the worn brush off the rods 11. A new brush may then be slid onto the rods and the head replaced.

The above described structure is but one embodiment illustrative of many forms of the invention and it is to be understood that various modifications of the invention are contemplated within the scope of the invention as defined by the appended claims.

I claim:

1. A device of the character described comprising a handle, a member slidably supported by said handle and provided with longitudinal rows of bristles, and actuators carried by said handle for engagement by said bristles to move the same transversely upon relative movement of said handle and member, said actuators having oblique portions engageable by said bristles.

2. A device of the character described comprising a handle, a member slidably supported by said handle and provided with longitudinal rows of bristles, and undulating members extending from said handle between adjacent rows of bristles for transversely vibrating said bristles upon relative reciprocation of said handle and member.

3. A device of the character described comprising a handle, a member slidably and removably supported by said handle, said member being provided with longitudinal rows of bristles, and actuators carried by said handle for engagement by said bristles to move the same transversely upon relative movement of said handle and member, said actuators having oblique portions engageable by said bristles.

4. A device of the character described comprising a handle, a member slidably and removably supported by said handle, said member being provided with longitudinal rows of bristles, and undulating members extend-

ing from said handle between adjacent rows of bristles for transversely vibrating said bristles upon relative reciprocation of said handle and member.

5. A device of the character described comprising a handle, a pair of rods carried by said handle, a member slidably supported by said rods and provided with longitudinal rows of bristles, and undulating members extending from said handle between adjacent rows of bristles.

6. A device of the character described comprising a handle, a pair of rods carried by said handle, a member slidably supported by said rods and provided with longitudinal rows of bristles, a head carried by the free ends of said rods, and undulating members extending from said handle between adjacent rows of bristles.

20. 7. A device of the character described comprising a handle, a pair of rods carried by said handle, a member slidably supported by said rods and provided with longitudinal rows of bristles, a head detachably supported by the free ends of said rods, and undulating members extending from said handle between adjacent rows of bristles.

8. A device of the character described comprising a handle, a pair of rods attached at one end to said handle, a member slidably supported by said rods and provided with longitudinal rows of bristles, a head attached to the other ends of said rods, and wavy wires extending from the handle to the head between rows of bristles.

In testimony whereof I have signed my name to this specification.

ROSALYE SCHWERIN.
